IGNITION DEVICE

Elmer Olson, Ferndale, and Stanley M. Udale,
Detroit, Mich., assignors to George M. Holley
and Earl Holley

Application November 30, 1944, Serial No. 565,892

4 Claims. (Cl. 123—117)

The object of this invention is to improve the promptness in response to suction used to advance the ignition in proportion to the air flow through a venturi and also with the suction in the inlet manifold. The negative response to a reduction in suction is also important, and here also instantaneous response is desirable.

It has previously been proposed to have two separate diaphragms, one responsive to the manifold and one responsive to the Venturi suction.

It has also been suggested to have a diaphragm simultaneously responsive to both the Venturi suction and the manifold suction, and it has also been proposed to have a diaphragm responsive to manifold suction as modified by the Venturi suction, and when the manifold suction became low as the throttle approached wide open for an automatic, spring-loaded check valve to eliminate the manifold suction. The difficulty is that the response is not instantaneous and knocking occurs during the transition period, which is fatal to commercial success. One difficulty is that more suction is available at part throttle than can usefully be employed.

Figure 1 shows diagrammatically the application of one form of our invention to the ordinary ignition system and carburetor in general use on automobiles.

Figure 2 shows an alternative construction.

Figure 3 shows another design.

In Figure 1, 10 is an air entrance, 11 is a venturi, 12 is a fuel nozzle discharging therein, 13 is a mixture outlet, 14 is a throttle valve therein, 15 is a relatively unrestricted passage connecting the throat of the venturi 11 with a chamber 16, in which is located a double-ended valve 17. This double-ended valve 17 seats on the two ends of a perforated sleeve 18, which is perforated by openings 19, which provide free communication from the passage 15 to the chamber 16.

A passage 20, adjacent to and on the atmospheric side of the upstream lip of the throttle 14 (when throttle is in its idling position), communicates with a chamber 21, in which is located a compression spring 22, which causes the lower end of the valve 17 to seat on the lower seat of the sleeve 18; a pipe 23 connects the chamber 16 with a chamber 24, in which is located a spring 25 and a diaphragm 26. The diaphragm 26 responds to suction and rotates a circuit-breaker plate 27 anti-clockwise, thereby advancing the spark, the limit of the advance and retardation being determined by the stops 48—49.

29 is a storage battery, 30 is a standard high

tension distributor including the usual coil, 31 is a movable contact, 32 is a relatively stationary contact on the plate 27 and 33 is a rubbing block which is engaged by a cam 34; 35 is a spring lever, which causes the rubbing block 33 to engage with the rotating cam 34.

In Figure 2, the double-ended flat valve 37 takes the place of the double-ball valve 17 (Figure 1) and the spring 22 has been eliminated. 10 The passage 38 leads from the throat of the venturi 11 to the chamber 39 below the valve 37, which is so constructed that it has only a limited lift. The chamber 41 above the valve 37 is in communication with the engine suction 15 the moment the throttle 14 opens so that the pipe 23 transmits the engine suction the moment the throttle 14 opens.

The restrictions 45 and 44 are selected so that the suction in 24 does not exceed by many inches of mercury the maximum suction attained in the throat 11 of the venturi. The circuit breaker plate 27 is advanced against the stop at wide open throttle maximum speed. In certain cases (passenger cars), a greater part throttle advance is required, say 40% more, than wide open advance. In the latter case, the part throttle suction will be approximately 40% greater than wide open throttle Venturi suction at maximum speed.

In Figure 3, the valve 42 is given only a limited lift and covers the passage 43, which communicates through a restriction with the throat of the venturi 11. Here the restriction 46 in the outlet of passage 43 into venturi 11 is larger than the restriction 47, which admits engine suction 35 to lift the valve 42.

Operation

In Figure 1, when the throttle 14 is partially open, the moment the engine fires, the upper seat of the valve 17 engages with the upper seat of the sleeve 18 and thus a high suction is transmitted to the chamber 24, and the spark is advanced to the maximum desirable spark advance. When the throttle is opened suddenly, the valve 45 17 is pushed up by the spring 22 and seats on the bottom of the sleeve 18. Immediately, there is a wide open passage from 23 through passages 19 past the valve 17 through the passage 15 to the venturi 11. In other words, the pressure in chamber 24 immediately falls almost to atmospheric pressure, and the spark is suddenly and completely retarded.

Now the criticism that has been directed against all ignition devices of the type in which the centrifugal governor weights have been re-

moved is that they perform perfectly with one defect, and that is there is an annoying sequence of knocks following the acceleration of the car. This annoying sequence of knocks induces the owner to retard the spark and thereby loss of mileage that he would otherwise secure. The result is that although this type of ignition control (eliminating the centrifugal weights) has been advocated for 20 years, the centrifugal device with all its difficulties has been universally used. This advantage, therefore, although slight, is commercially of considerable importance. The unrestricted pipe 23, unrestricted passage 15, the large openings 19 in the sleeve 18 and the unrestricted passage 20 constitute the novel means required to get the desired improvements; the valve 17 is the element that makes the device commercially possible.

In Figure 2, the double-ended valve 37 is raised the moment the valve 14 opens away from the idling position so that its upper surface is subjected to the engine suction. Otherwise, the action of valve 37 is very similar to the action of valve 17. However, part throttle suction is approximately 20" Hg as compared with 5½ to 7" maximum Venturi suction, so that in all cases more part throttle suction is available than can be usefully employed in advancing the spark. Hence, the suction at 45 is reduced by the vent 44. Hence, the opening 44 would be somewhat larger than 45.

In Figure 3, a single flat valve is used, sealed by gravity. Being thin, its weight is very small so that the slightest suction causes it to lift. However, the outlet from the passage 43 to the venturi 11 is necessarily restricted. This is objectionable, as the vacuum trapped in chamber 24 cannot instantaneously relieve itself as is the case with the constructions shown in Figures 1 and 2, which are the preferred constructions.

In Figure 3, the suction in the Venturi throat, which advances the spark when the throttle is wide open, is as great as or almost as great as the part throttle suction transmitted through the restriction 47, because the restriction 46 is greater than the restriction 47.

What we claim is:

1. A spark advance device for an automotive engine comprising a carburetor having an air entrance, a venturi therein, a first unrestricted passage communicating with the throat of said venturi, a throttle located downstream of said venturi, an air chamber, a moving wall therein, spring means controlling the movement of said moving wall, an ignition timing device connected to said moving wall, a second unrestricted passage connecting the chamber with the first unrestricted passage, a double-ended valve located at the junction of the two passages, automatic means for moving said double-ended valve to a position which places the two passages in unrestricted communication with each other when the engine is not in operation, a second air chamber located adjacent said valve, a passage located with reference to said throttle so as to connect said second chamber with the air entrance on the atmospheric side of said throttle when said throttle is in its idling position and with the engine side of said throttle immediately after the throttle is moved away from its idling position, means responsive to the engine suction and to the initial opening of the throttle with refer-

ence to said passage so as to move said valve against said yieldable means by the application of the engine suction to said valve, said valve being adapted to simultaneously close the unrestricted passage leading to the venturi and to connect the second unrestricted passage with the engine side of the throttle through said second chamber whereby when the throttle is opened wide, the double-ended valve seats and the first unrestricted passage is again placed in unrestricted communication with the second unrestricted passage, and the vacuum created in said chamber escapes rapidly through said unrestricted passages.

2. A device as set forth in claim 1 in which the second air chamber has a first opening of restricted area communicating with the atmosphere and a second opening of restricted area larger than the first opening, said second opening being in the passage connecting said second chamber with the engine side of said throttle immediately after the throttle is moved away from its idling position.

3. A spark advance device for an automotive engine comprising a carburetor having an air entrance, a venturi, a first unrestricted passage communicating with the throat of said venturi, a throttle located downstream of said venturi, an air chamber, a moving wall therein, spring means controlling the movement of said moving wall, an ignition timing device connected to said moving wall, a second unrestricted passage connecting the chamber with the first unrestricted passage, a double-ended valve located at the junction of the two passages, said valve being adapted to seat by gravity in a position which places the two passages in unrestricted communication with each other when the engine is not in operation, a second air chamber located adjacent said valve, a passage located with reference to said throttle so as to connect said second chamber with the air entrance on the atmospheric side of said throttle when said throttle is in its idling position and with the engine side of said throttle immediately after the throttle is moved away from its idling position, means responsive to the engine suction and to the initial opening of the throttle with reference to said passage for moving said valve against the force of gravity by the application of the engine suction to said valve, said valve being adapted to simultaneously close the unrestricted passage leading to the venturi and to connect the second unrestricted passage with the engine side of the throttle through said second chamber whereby when the throttle is opened wide, the double-ended valve seats and the first unrestricted passage is again placed in unrestricted communication with the second unrestricted passage, and the vacuum created in said chamber escapes rapidly through said unrestricted passages.

4. A device as set forth in claim 3 in which the second air chamber has a first opening of restricted area communicating with the atmosphere and a second opening of restricted area larger than the first opening, said second opening being in the passage connecting said second chamber with the engine side of said throttle immediately after the throttle is moved away from its idling position.

ELMER OLSON,
STANLEY M. UDALE.
